CAP STAY

Maurice H. Krieger, Brooklyn, N. Y., assignor to Art Cap Company, Inc., New York, N. Y., a corporation of New York

Application March 4, 1955, Serial No. 492,133

1 Claim. (Cl. 2—199)

This invention relates to a cap stay and more particularly to a stay for caps of the type usually worn by members of the armed forces.

Heretofore cap stays for supporting the crown portion of a cap cover have been provided of leather covered cardboard or the like. Such stays were usually wedge-shaped and did not have the desired contour. In use these stays oftentimes collapsed making the hat unsightly. In order to overcome this problem, it has been proposed to utilize the cap stay made of a completely rigid material, such as metal. However, these stays did not conform to the head of the wearer and made the crown portion of the hat completely flat and unattractive in appearance. In addition, these latter stays are so constructed as to tear the material of the cap cover when placed thereover.

It is an object of the present invention to provide a cap stay for caps of the character described which will conform in shape to the head of the wearer.

It is a further object of the present invention to provide a cap stay which will not damage the cap cover placed thereover and which will provide the cap cover with an attractive contour.

Still another object of the present invention is to provide a cap stay which is durable and has longevity in use.

Yet another object of the present invention is to provide a cap stay having all of the desired advantages which is nevertheless economical to manufacture and easy to produce.

Other objects and advantages are set forth in greater detail in the accompanying specification taken in conjunction with the accompanying drawings, in which:

Fig. 1 is a side elevation partially broken away of the cap stay of the present invention in position within a cap;

Fig. 2 is an enlarged section of the front portion of the cap showing the cap stay of the present invention; and

Fig. 3 is a perspective view of the cap stay of the present invention.

Referring to the drawings, there is shown a cap 7 of the general type worn by members of the armed forces throughout the world. The cap 7 comprises a removable cap cover 8 having a crown portion 9, a head-engaging portion 10, and a visor 11. A sweatband 12 is disposed within the head-engaging portion. A fiber band 13 is located in front of the head-engaging portion 10. A shape-retaining ring 14 is disposed within the upper part of the crown portion of the cap. A visor strap 15 is usually located across the front of the head-engaging portion 10, as shown.

In the utilization of standard military caps of the type described, it is necessary to provide a stay to support the crown 9 of the cap in order to prevent its collapse. Various proposed stays of completely rigid material with cut-out portions in the form of notches did not prove completely desirable, nor did other stays of flexible material which tended to collapse. According to the present invention, however, there is provided a cap stay 16 made of one piece of material which completely supports and

2

maintains the crown portion 9 of the cap. The material used, according to the present invention, is such that which sufficient rigidity is maintained to prevent collapse of the crown portion 9, nevertheless the cap stay is sufficiently flexible to conform to the shape of the head of the wearer and still allow the cap stay to remain in its normal shape. The cap stay of the present invention for distending the crown of the cap cover, comprises a tapered member of relatively flexible material, preferably plastic.

10 The lower portion 17 of said tapered member is angularly offset with respect to the upper portion 18. The lower portion is secured between the head-engaging portion 10 and the fiber band 13 of the cap by means of staples 20 or any other suitable securing means.

15 It is to be noted that the lower portion 17 is flexible and will conform to the shape of the head of the wearer.

The upper portion of the cap stay is curved so as to have a convex front surface engaging the inside front surface of the cap crown 9, and so as to have a concave

20 rear surface exposed at the interior of the cap, such surfaces being hereinafter also referred to as convex and concave opposite sides. The cap stay portion 18 also has an arcuate top surface 24, as shown, thereby causing the crown of the cap cover placed thereover to present

25 an attractive rounded appearance with desirable contour. It is to be noted that with the use of the cap stay of the present invention, the crown portion will not collapse and that the cap stay presents an unbroken surface to the crown of the cap cover.

30 If desired the upper portion 18 may be provided with a central opening 21 as shown to accommodate an emblem to be worn on the crown of the cap cover.

The upper portion 18 of the cap stay of the present invention is provided with peripheral flanges 22 and 23 along the sides of the upper portion of the cap stay. Another peripheral flange or arcuate top surface 24 is provided along the top of the upper portion of the cap stay. As shown, the peripheral flanges 22 and 23 end short of the peripheral flange 24 whereby notches 25 and 26 are provided. The notches 25 and 26 engage the shape-retaining ring 14 at the top of the cap and prevent inadvertent vertical movement of the shape-retaining ring as well as maintaining the cap stay in position. The bases of the peripheral flanges 22 and 23 are supported 45 on the head-engaging portion 10.

An important feature of the cap stay of the present invention is its adaptability to be used with interchangeable and removable cap covers. Heretofore the cap cover itself has in many instances been padded to accomplish the desired shape and contour. With the use of the present invention the desired result is obtained without affecting the cap cover which may be easily removed and interchanged so the different types of covers may be utilized as for example summer and winter cap covers.

55 The cap stay of the present invention, therefore, provides a relatively flexible but nevertheless substantially rigid supporting member for the crown of the cap cover which causes the cover to present an attractive arcuate shape and contour, which will in no way damage the cap cover and which will not collapse.

60 While the invention has been described in some detail, it will be understood that variations and modifications may be made by those skilled in the art without departing from the spirit of the invention or the scope of the appended claim.

65 I claim:

A stay for shaping the front upper edge of a cap cover comprising a tapered, flexible hollow and shell-like member having lower and upper portions, the upper portion thereof having preformed convex and concave opposite sides, the lower portion of said member being readily bendable and extending angularly relative to the upper

portion and being adapted for securing to the head-engaging portion of a cap adjacent the front of the cap cover, the upper extremity of said upper portion constituting an arcuate substantially horizontal top edge adapted to lie in the same plane as the cap cover whereby the front upper edge of the cap cover is rounded in appearance with a contour as determined by the said arcuate edge, and said shell-like member having peripheral flanges extending along its sides and top, said top flange engaging and shaping the front of the cap cover, and said side peripheral flanges ending short of said top peripheral flange and thereby providing notches for engaging the

shape retaining ring of the cap and preventing relative vertical movement of said tapered flexible member and retaining ring.
